WET BULB THERMOSTAT CONTROL
SYSTEM

Samuel M. Anderson, Sharon, Mass., assignor to
B. F. Sturtevant Company, Hyde Park, Boston,
Mass.

Application May 3, 1939, Serial No. 271,611

4 Claims. (Cl. 236—38)

This invention relates to wet bulb thermostat controls and has as its general object the provision of an effective and efficient wet bulb thermostat control system for air conditioned railway passenger cars.

It is desirable for eliminating odors, for providing germ free air and for providing the highest quality conditioned air, to use less recirculated air for air conditioning and to use more outdoor air in the air conditioning of railway passenger cars. In the past, the practice has been to use 25% outdoor air and 75% recirculated air. The use of such large quantities of recirculated air has resulted not only in unpleasant odors but in the recirculation of harmful germs added by the occupants of the passenger space. In addition, no amount of conditioning of recirculated air can provide the tone and quality of outdoor air.

According to this invention all outdoor air is used in an air conditioning system for railway passenger cars, and this is economically accomplished by a novel wet bulb thermostat control system which fits in advantageously with existing car apparatus and which provides 100% outdoor air when the outdoor wet bulb temperatures are within the range in which all outdoor air may be conditioned without too great a load upon the cooling or heating system, and which provides partial recirculation in extreme temperature ranges.

The invention will now be described with reference to the drawing which illustrates diagrammatically one embodiment of the invention applied to a railway passenger car.

The overhead air conditioner 5 may be supplied with a volatile refrigerant from the usual compressor 6 and condenser 7. The car thermostat 8 may control car temperatures in the cooling season by controlling the energizing circuit connecting the motor 9 to the usual axle generator 10 and its associated battery (not shown).

The blower 11 draws outdoor air through the dampers 12 and recirculated air through the dampers 13 and supplied it to the conditioner 5.

The thermostat 15 may be of any well known wet bulb type having a water wetted wick and responds to changes in the wet bulb temperature of the outdoor air and acts when the wet bulb temperature is below say 70° F. to open the circuit connecting the damper motor 14 to the axle generator 10, to cause the motor 14 to adjust the dampers to 100% outdoor air. When the wet bulb temperature is above 70° F., the

circuit of the motor 14 is closed causing the motor to partially close the dampers 12 and to partially open the dampers 13 for partial recirculation.

The evaporator surface of the thermostat 15 is wetted by water supplied through the valve 16 and tube 17 from the water tank 18. It is preferred that the internal diameter of the tube 17 be so constricted that the volume of water supplied thereby to the thermostat 15 is that which would be expected to be evaporated therein. Compressed air from the source 19, which may be the supply source for the air brakes of the car, supplies air into the tank 18 for building up a sufficient pressure to force the water through the tube 17 to the overhead thermostat 15. The solenoid 20 opens the valve 16 in the water line when the start-up switch 21 is closed to energize the entire system.

More refrigeration is required and the equipment is in operation for greater periods of time when the thermostat has acted to supply 100% outdoor air to the system and it is realized that at the low car speeds when the generator 10 is not driven fast enough to charge its battery, the thermostat 15 when the wet bulb temperature is below 70° F. would cause too great a load on the battery and would cause it to become discharged. Accordingly, the relay 22 is provided for shorting out the thermostat 15 at car speeds below the critical one. In a standard air conditioned railway car, a control panel 23 connected to the electric supply equipment, is placed in a corridor in one end of the car, and above, the panel is mounted a green electric light 24 which glows when the car is moving below the critical battery charging speed of 20 miles per hour, and which goes out when the car speed is above 20 miles per hour. The relay 22 is connected in series with this light 24 and is energized to close contacts which are connected to the wires 25 to short out the thermostat 15 and to close the circuits which normally would be closed by the thermostat 15 when the wet bulb temperature of the outdoor air was above 70° F. This causes the damper motor to adjust the dampers 12 and 13 for partial recirculation thus reducing the air conditioning load and as a result, the load upon the electric supply equipment.

While one embodiment of the invention has been described for the purpose of illustration, it should be understood that the invention is not limited to the exact apparatus and arrangement of apparatus illustrated since modifications

thereof may be suggested by those skilled in the art without departure from the substance of the invention.

What is claimed is:

- 6 1. In an air conditioning system for passenger vehicles having a motor driven accessory, a wet bulb thermostat in control thereof, an electric supply, and apparatus including an electric switch for closing a circuit including said supply, said wet bulb thermostat and the motor for said accessory, a water tank, a conduit connecting said tank with said wet bulb thermostat, a compressed air source connected to said tank for forcing water through said conduit to said 10 thermostat, and means for initiating the supply of water from said tank to said thermostat upon the closing of said switch.
- 15 2. An air conditioning system for a vehicle, comprising an air cooler, means for supplying outdoor and recirculated air into said cooler, an outdoor wet bulb thermostat for adjusting said means for increasing the proportion of outdoor air when its wet bulb temperature is below a predetermined point, and means responsive to vehicle speeds for rendering said thermostat ineffective when the speed falls below a predetermined speed.

3. An air conditioning system for a vehicle, comprising an air cooler, means for supplying outdoor and recirculated air into said cooler, an outdoor wet bulb thermostat for adjusting said means for increasing the proportion of outdoor air when its wet bulb temperature is below a predetermined point, and means responsive to vehicle speeds for rendering said thermostat ineffective and for adjusting said first mentioned means for decreasing the proportion of outdoor air when the speed falls below a predetermined speed. 5

4. An air conditioning system for a vehicle, comprising an air cooler, means for supplying outdoor and recirculated air into said cooler, 15 and means responsive to outdoor wet bulb temperatures and to vehicle speeds for adjusting said first mentioned means for increasing the proportion of outdoor air when the outdoor wet bulb temperature is below a predetermined temperature and the speed is above a predetermined speed and for decreasing the proportion of outdoor air when the outdoor wet bulb temperature is above said predetermined temperature or the speed is below said predetermined speed. 20 25
